(57) **CLAIM**

I claim the ornamental design for a stair nosing cover, as shown and described.

DESCRIPTION

FIG. 1 is a perspective view of one embodiment of a stair nosing cover, as viewed from the front, above, and one side. FIG. 2 is a top plan view of the stair nosing cover of FIG. 1.

FIG. 3 is a bottom plan view of the stair nosing cover of FIG. 1.

FIG. 4 is a side elevation view of the first side of the stair nosing cover of FIG. 1.

FIG. 5 is a side elevation view of the second side of the stair nosing cover of FIG. 1.

FIG. 6 is a rear elevation view of the stair nosing cover of FIG. 1.

FIG. 7 is a front elevation view of the stair nosing cover of FIG. 1.

FIG. 8 is a perspective view of an exemplary stair nosing cover, as viewed from the front, above, and one side, shown attached to an exemplary stair nosing.

FIG. 9 is a side elevation view of the first side of the stair nosing cover of FIG. 1, shown attached to an exemplary stair nosing.

FIG. 10 is a perspective view of another embodiment of the stair nosing cover, as viewed from the front, above, and one side.

FIG. 11 is a top plan view of the stair nosing cover of FIG. 10.

FIG. 12 is a bottom plan view of the stair nosing cover of FIG. 10.

FIG. 13 is a side elevation view of the first side of the stair nosing cover of FIG. 10.

FIG. 14 is a side elevation view of the second side of the stair nosing cover of FIG. 10.

FIG. 15 is a rear elevation view of the stair nosing cover of FIG. 10.

FIG. 16 is a front elevation view of the stair nosing cover of FIG. 10.

FIG. 17 is a perspective view of the stair nosing cover of FIG. 10, as viewed from the front, above, and one side, shown attached to an exemplary stair nosing; and,

FIG. 18 is a side elevation view of the first side of the stair nosing cover of FIG. 10, shown attached to an exemplary stair nosing.

The dashed lines in the drawings are for illustrative purposes only and form no part of the claimed design. The short dash, long dash lines in the drawings indicate that the embodiments shown are of an indeterminate length.
